DESIGN FOR A DISPENSING COVER FOR A PITCHER OR SIMILAR ARTICLE

Ralph H. Pershall, Bremerton, Wash., assignor to Sanicut Mfg. Co., Port Orchard, Wash., a corporation of Washington

Application January 29, 1938, Serial No. 74,695

Term of patent 14 years

To all whom it may concern:

Be it known that I, Ralph H. Pershall, a citizen of the United States, residing at Bremerton, in the county of Kitsap and State of Washington, have invented a new, original, and ornamental Design for a Dispensing Cover for a Pitcher or Similar Article, of which the following is a specification, reference being had to the accompanying drawing, forming part thereof.

Figure 1 is a perspective view of the dispensing cover for a pitcher or similar article showing my design; and

Figure 2 is a top plan view thereof.

I claim:

The ornamental design for a dispensing cover for a pitcher or similar article, as shown.

RALPH H. PERSHALL.
